Fig. 9d.

Rotary Stepping Switches RS-8 and RS-9. Count time in years from 00 to 99 in code.

RS-9
Counts years by tens from 0 to 9, inclusive. When RS-9 receives its 10th carry digit from RS-8, it will advance to neutral and reset to 0. This would occur for the first time in the year 2000.

RS-8
Counts years in units from 0 to 9, inclusive. When RS-8 receives its 10th carry digit from RS-7, it will advance to neutral, resets to 0 and passes a carry (10 year) digit to RS-9.

RS-7
Counts days in hundreds from 0 to 3 inclusive. When RS-7 reaches its 3 position, RS-6 its 6 position, RS-5 its 6 position, RS-4 its 2 position, RS-3 its 3 position, RS-2 its 5 position, and RS-1 its 9 position, relays RY-1, 2, 3, 4, 5, 6 and 7 are energized simultaneously. To deliver a carry digit to RS-8 and to order relays RY-1, 2, 3, 4, 5, 6 and 7 reset to zero. [Each regular year (not leap years) the technician will set this counter ahead one day on the last day of the year.]

To RY-7

RS-6
Counts days by tens from 0 to 9, inclusive. When RS-6 receives the 10th carry pulse from RS-5 it advances to neutral, resets to 0, and passes a carry (100 days) digit to RS-7.

To RS-6

RS-5
Counts days by units from 0 to 9, inclusive. When RS-5 receives the 10th carry pulse from RS-4 it advances to neutral, resets to 0, and passes a carry (10 days) digit to RS-6.

To RS-5

BUSINESS MACHINES

John D. Dillon, 1001 Riverside Drive, Melbourne, Fla., assignor, by mesne assignments, of one-half to William J. Ruano, Pittsburgh, Pa.

Filed Nov. 5, 1956, Ser. No. 620,310

6 Claims. (Cl. 178—26)

This invention relates generally to business machinery to facilitate records keeping and accounting and, more particularly, to a system and mechanism for storing fixed and variable source data in code form and for subsequently translating or recording such data in any desirable form.

An outstanding disadvantage of present day business accounting methods is that great dependence is made upon the human element, such as entries by a clerk on cards, etc. and the transfer of such entries onto other records or machines, such as computing machines. Human errors, therefore, generally arise in such entries and transfers. Moreover, conventional record keeping systems are extremely time-consuming and involve considerable expense for their maintenance.

Although machines have been used to perform calculations on fixed data, such machines have left much wanting, particularly as to simplification of systems preceding use of the machines and in elimination of errors and expenses involved therein.

An object of the present invention is to provide business systems and apparatus that are devoid of the above named disadvantages and which will enable very speedy and accurate entry, storage, transfer, collating and recording of information at only a small fraction of the time and cost of use of conventional systems and apparatus.

A more specific object of the invention is to provide a novel system to facilitate records keeping and accounting in manual, machine and manual-machine systems.

Another object of the invention is to provide a novel system which will capture fixed and variable source data at its origin and immediately and automatically translate the data into machine language, such as teletypewriter code, and transmit such machine language data to a near or remote device, such as a paper card, tape punch, or the like, which may be transmitted to a teletypewriter, computer, converter, recorder or other machine.

Another specific object of the invention is to provide novel apparatus for storing, in machine language, such as teletypewriter code, information fed into the machine from a plurality of coded input sources, such as cards, time clocks, dials, wired-in or already stored fixed data etc., thereafter collating and combining such information and translating the resultant into usable form, such as by feeding it into another machine, such as a teletypewriter, computer, converter etc.

A still further object of the invention is to provide a novel type input card which distinguishes from ordinary punched cards (such as IBM cards) used to operate business machinery. The cards according to the present invention are of conducting material, instead of paper, and the positions of the holes are not correspondingly meaningful.

Still another object of the invention is to provide a time and records keeping system including a time clock which operates in code language, such as teletypewriter code.

A still more specific object of the invention is to provide a novel automatic business machine selectively operated in teletypewriter code, by one of a plurality of punched cards or one of a plurality of dials, as selected by a controller, to feed in fixed and variable data,

2

also operated by a time clock in teletypewriter code to feed in variable time data, all of which data is combined, transmitted over a teletypewriter communication system and finally converted into either a form for reading, as by a teletypewriter, or used to actuate a business machine, such as a computer.

Other objects and advantages of the invention will become more apparent from a study of the following description taken with the accompanying drawings.

10 It should be noted that for the sake of brevity, I have coined a number of new words or trademarks, such as Codomatic, Amicode, Cardamatic, etc., which are referred to in the following description of figures and which are fully defined thereafter.

15 DESCRIPTION OF FIGURES

FIGURE 1 is a functional block diagram of the Codomatic System, showing the functional interrelationships of the various modules of the system.

20 FIGURE 1a shows a card input, one of the Card Readers shown in FIG. 2b.

FIG. 1c shows a number of Dial Stations, each of whose inputs is a dialled message followed by a Go signal.

25 FIG. 1d is the Controller, which permits but one Card Reader or Dial Station to operate at a time and which controls the sequence of electrical operations within the Codomatic System.

FIG. 1e is the Master Timer which records the time 30 continuously in teletypewriter code.

FIG. 1f is the Communications system which may be only a few feet in length for local operation, or a commercially available long lines system such as A. T. & T. or Western Union.

35 FIG. 1g is the paper tape punch, which accepts electrical signals from the Card Reader Stations, Dial Stations and the Master Timer to produce a punched paper tape output in 5-Channel teletypewriter code.

FIG. 1h indicates the paper tape output.

40 FIG. 1i illustrates the operation of the signal lamp circuits. FIG. 1i (1) shows the signal lamps in ready condition at all stations. FIG. 1i (2) shows the signal lamp conditions at all stations when station #1 is in use. FIG. 1i (3) shows the signal lamp conditions at all stations when the action at station #1 is completed and station #N is in use.

45 FIG. 2 is an expanded functional block diagram of the Codomatic System, and shows somewhat more detail than FIG. 1.

50 FIG. 2a shows an Amicode card input to any one of the Cardamatic Stations. Cardamatic Station #1 is shown since it is a typical station. FIG. 2b shows that within each Card Reader are the control circuits essential to its operation, designated as Master Control #1 in the 55 figure, a Card Reading Rotary Switch, start push-button switches, called In and Out, and signal lamps with the associated circuitry.

FIG. 2c is a block diagram of Dialamatic Station #1, which is a typical station. It consists of a Dial, a Go switch, dial control and release circuits, a selector rotary switch, RS-D1, Dial Message Digit stores designated RS-D2 to RS-D8, inclusive, a Master Dial Message Store, RS-D9, and a Time Delay Relay.

60 FIG. 2d is the Controller which governs the sequence of actions in the Codomatic System. It consists of a Holding Relay, Traffic Manager (a rotary stepping switch), a Searcher (a rotary stepping switch), a Reading Pulses Generator and a Records Keeper, as indicated in the diagram.

65 FIG. 2e is the Master Timer consisting of an electro-mechanical device (the "Clock") which generates electrical pulses at the rate of one per minute, a clock ad-

vance inhibit circuit, a set of five rotary switches, RS-I to RS-V, inclusive which count time in units, ten, hundreds, thousands and ten thousands of minutes in teletypewriter code, and a time store called the time records keeper, RS-T.

FIG. 2f is the Communications System shown also in FIG. 1f.

FIG. 2g is the Punch shown also in FIG. 1g.

FIG. 2h is a sample punched paper tape outside just as it would appear with the message shown on its right for purposes of illustration. A more general description of its use appears in the column along the left of the punched entries.

FIG. 2i is the Time Display and Reset circuitry and devices which may be considered integral with the Master Timer.

FIG. 3 is the Controller.

FIG. 3a is the Rotary Searching Switch #1, RS-S, the Searcher, with connections to Release Relays at Stations 1 to 10, inclusive and to RL (which is explained later) shown.

FIG. 3b is the Traffic Manager of the Controller.

FIG. 3c is the Records Keeper of the Controller.

FIG. 3d is the Holding Relay of the Controller.

FIG. 3e is the Reading Pulses Generator serving the Controller. It is shown in block form only.

FIG. 3f shows the release relays at Stations 1 to 10, inclusive, in block diagram form.

FIG. 3g is an example of one type of Reading Pulses Generator which may be used.

FIG. 3h is the Local Power Supply of the Controller.

FIG. 4 is the Master Timer.

FIG. 4a is a Rotary Switch, RS-I, which counts minutes by units in teletypewriter code.

FIG. 4b is Rotary Switch, RS-II, which counts tens of minutes in teletypewriter code.

FIG. 4c is Rotary Switch, RS-III, which counts hundreds of minutes in teletypewriter code.

FIG. 4d is Rotary Switch, RS-IV, which counts thousands of minutes in teletypewriter code.

FIG. 4e is Rotary Switch, RS-V, which counts tens-of-thousands of minutes in teletypewriter code.

FIG. 4f is the Recording and Reading Rotary Switch, RS-T, which records and stores the continuing record of the time and other wired-in data in teletypewriter code.

FIG. 4g is the electromechanical device referred to as the "Clock" in FIGS. 1 and 2. It is a motor driven cam with a contact switch as shown and drives RS-I.

FIG. 4h is detail of the Reset and Release circuitry of the Master Timer.

FIG. 4i is detail of the Clock Advance Inhibit Circuits.

FIG. 4j is the Communications System.

FIG. 4k is the Punch.

FIG. 4l is a sample punched paper tape output in teletypewriter code.

FIG. 4m is Homing Relay (or Switch) detail.

FIG. 5 is the Display and Reset Mechanism.

FIG. 5a is detail of Rotary Switch, RS-TM.

FIG. 5b is a Vedor Counter display, front view.

FIG. 5c is a side view of one Vedor Counter wheel, detail omitted, showing how the numbers on the vedor counter run from 0 to 9, inclusive.

FIG. 5d is one of many possible arrangements for use in obtaining the initiating pulse required to automatically reset the Master Timer.

FIG. 6 is the Amicode, Amicode Card, and Amicode Card Reader. The various separate drawings of FIGURE 6 are not drawn to any particular scale.

FIG. 6a is an Amicode card encoded and punched in the inverse teletypewriter code.

FIG. 6b is the output paper tape obtained by reading the Amicode card shown in FIG. 6a with the Amicode card reader.

FIG. 6c is a top view of the Amicode Card Reader with the top removed and with one kind of contact.

FIG. 6d is detail of the kind of contact shown in FIG. 6c.

FIG. 6e is a top view of the Amicode Card Reader.

FIG. 6f is a front view of the Amicode Card Reader.

FIG. 6g is a side view of the Amicode Card Reader.

FIG. 6h is a rear view of the Amicode Card Reader.

FIG. 6i is a top perspective view of a simple Amicode Card.

FIG. 6j is a top perspective view of the pole contactors of the Card Reader. Springs are not shown in FIG. 6j.

FIG. 6k is detail of a pole contactor in cross section.

FIG. 7 is a schematic diagram of the Simplest Cardamatic Station.

FIG. 7a is the Card Reading Rotary Switch, RS-CR1.

FIG. 7b is a cut-away view of connections from the pole contactors of the Card Reader to the Card Reading Rotary Switch.

FIG. 7c is Master Control #1 of Card Reader #1 or Cardamatic Station #1.

FIG. 7d is the Communications System.

FIG. 7e is the Punch.

FIG. 7f is a sample five channel (teletypewriter code) punched paper tape output from the Punch.

FIG. 7g is the local power supply for the Cardamatic Station.

FIG. 8 is a schematic diagram of a Dialamatic Station. All rotary switch contacts marked are connected to B+ voltage.

FIG. 8a are the Signal Lamps.

FIG. 8b is the Dial Connections.

FIG. 8c is the Traffic Routing Rotary Switch, RS-D1.

FIG. 8d is the Dial Control and Release Circuitry.

FIG. 8e is the Dial Message Recorders, RS-D2 to RS-D8 inclusive.

FIG. 8f is the Dial Message Store, Rotary Switch, RS-D9.

FIG. 8g is detail of some of the connections of RS-D2 to RS-D8, inclusive and RS-D10.

FIG. 8h is the Communications System.

FIG. 8i is the Punch.

FIG. 8j is a five channel (teletypewriter code) punched paper tape output.

FIG. 8k is the Holding Relay, RY-DH1.

I. THE CODAMATIC SYSTEM

(A) Terminology

In order to clearly describe the Codamatic system, the intended meanings of certain words and phrases used herein should be made clear.

Source data is the input to a manual or machine data processing (records keeping and accounting) system. Data may be variable or fixed. Variable quantities are those whose values differ from time to time. Fixed data is invariant or almost invariant as a function of time.

Product order quantities, accounts payable, time spent on various operations by men or machines, the amount of a bank check or deposit are examples of variable data. Your name, identifying number, social security number, and birthdate, a customer's name or address, an employee's name or address, are examples of fixed data.

Sentinels are symbols used to identify operations, documents, or locations. Examples are the superscript used to identify a footnote to a document, code symbols to designate documents as customer orders, replenishment orders, action orders, shipping reports, or letters such as I or O to specify whether a time recorded is time of beginning or ending of the time interval during which an employee, process, or machine is employed on a particular task.

Reading devices are machines which can "recognize" or accept information in one code and, if so ordered, translate the information into another code; for example, a punch card reader translates the information carried by the holes in the card into coded electrical signals, which may be transmitted to another device which may be a

computer, a collator, a data transceiver, or a punch. Other examples or reading devices are a phonograph pick-up, and magnetic heads of magnetic tape or drum stores.

A recording device is one which accepts information and transcribes it to some medium. For instance, the magnetic heads of magnetic drum or tape stores, may be used for recording in a magnetic medium as well as for reading from it. Other examples are phonograph record cutter, the paper tape punch, the typewriter, and desk calculator. A reading and/or recording device, then, if one chooses, may be called a translator.

Communicating devices are such things as telegrapher's keys and telephones. Communications systems consist of input and output communicating devices and some media through which signals are carried, simple examples being telephone and telegraph lines, and space.

Common input media and computers are punched paper tape, magnetic cards and tape, and punched cards. Common outputs are the same as the input media with the addition of typed or printed documents.

(B) Functions of the Codamatic System

The Codamatic System and the components thereof (FIG. 2) are designed to facilitate records keeping and accounting in manual, machine and manual-machine systems. The Codamatic system is designed to and will, capture fixed and variable source data at its origin, and automatically and immediately translate the data into machine language, transmit the data (now in machine language) to a near or remote device, for example, a paper card or tape punch, which in turn automatically and immediately prepares a printed or typed document and cards or tapes in teletypewriter code which may be used directly, i.e., without modification, into a teletypewriter, Flexowriter, a computer such as the Univac File Computer, or a converter which accepts punched paper tape in teletypewriter code and prepares a 6, 7, 8 or other-channel paper tape, IBM or Remington-Rand punched cards.

While the Codamatic system described herein prepares all outputs in standard teletype coded (5 channel) punched paper tape, the design principles used are such that the system may easily be changed to operate in other codes and to produce punch cards, magnetic tapes, magnetic cards, or other-channel coded punched paper tapes. The Codamatic system is not limited in principle to any one kind of output.

(C) Brief description of the operation of the Codamatic System

An employee may insert a prepared (punched) Amicode card, which carries information (FIGS. 1a and 2a) into any Amicode Card Reader (FIGS. 1b and 2b) and punch the appropriate sentinel (start) push-button switch, or, he may dial the appropriate start sentinel and a message at any Dialamatic Station (FIGS. 1c and 2c) and then push the Go button-switch.

At the Station thus placed in operation, the In-Use signal lamp will be turned on, at all Stations, the Ready signal lamps will be extinguished, and all Stations other than the one in use, will be disabled and their Wait lamps will be turned on. The sentinel, punched or dialled, the message on the card or the message dialled, and stored data wired-in will be translated into machine language (teletypewriter code as shown), and read to a Punch either locally situated or remotely connected over a communications system (FIG. 1f and 2f). Then the date and time in teletypewriter code will be read from the Master Timer (which keeps time in teletypewriter code (FIGS. 1e and 2e)) to the Punch (FIGS. 1g and 2g). Last, an end of operation signal will be transmitted from the Controller to all Stations to extinguish the one In-Use lamp, all the Wait lamps, to turn on all the Ready lamps, and to enable all Stations.

Meantime, the Punch will have prepared a punched

tape (in teletypewriter code) listing the Sentinel, the message read from the Amicode card or dialled, fixed wired-in (stored) data, the time, and such other variable information as may be programmed (FIGS. 1h and 2h).

5 If the dialler makes a mistake and recognizes the fact at any time before he pushes the Go button, he may erase his erroneous message by simply dialling "Mistake" (Operator or "0" or a separate button).

10 The punched paper tape may be used directly as the input to a communications system (teletypewriter transmitter), a converter (paper tape to punch cards, magnetic cards, etc.), or a teletypewriter receiver or Flexowriter. Thus one may obtain a printed or typed listing of the identical message on the prepared teletype tape 15 either concomitantly with the Punch action, or separately later.

(D) General description of the Codamatic System

20 Codamatic is an original descriptive coined word which when used in conjunction with the noun, System, means Card Or Dial Automatic Machine Assembly and Translation of Information into Computer-language (i.e. machine).

25 Amicode is an original coined word devised to describe the Automatic Machine Instruction Code invented by this claimant. Amicode cards are original punched cards encoded with the inverse of the desired output code. Amicode card Readers (FIG. 2b) are original electromechanical devices which accept Amicode cards.

30 Cardamatic is an original coined word meaning Card Reading and Ancillary Automatic operation. It may be used to describe a Station or System. The simplest Cardamatic Station consists of some number of prepared Amicode cards (FIG. 2a), and one Amicode card reader (FIG. 2b). A more complex Cardamatic Station consists of a set of prepared Amicode cards (FIG. 2a), one Amicode Card Reader (FIG. 2b), one Master Timer (FIG. 2e), and one paper card or tape Punch (FIG. 2g). A Cardamatic system consists of a number of sets of Amicode cards (FIGS. 1a and 2a), a number of Amicode Card Readers (FIGS. 1b and 2b), one Controller (FIGS. 1d and 2d), one Master Timer (FIGS. 1e and 2e), a

35 communications system if needed (FIGS. 1f and 2f), and one or more punches (FIGS. 1g and 2g). Thus, one set of Amicode cards (FIG. 2a), one Amicode Card Reader (FIG. 2b), one Master Timer (FIG. 2e), and one Punch (FIG. 2g) constitute in fact, a general purpose Cardamatic Time Clock, and the Cardamatic System is a general purpose Time and Records Keeper system.

40 Dialamatic is an original coined word meaning Dial Recording and Reading Automatically. The word may

45 be used to describe a station or a system. The simplest Dialamatic Station consists of one automatic Dial Station recorder with necessary control and reset circuits, signal lamps and switches (FIG. 2c). A more complex Dialamatic Station consists of one Dial Station as described in the sentence immediately preceding (FIG. 2c), plus one Master Timer (FIG. 2e) and one paper card or tape punch (FIG. 2g). Such a Station is in fact a general purpose Dialamatic Time Clock and will be thus designated hereinafter for convenience of the reader.

50 55 60 65 70 75 A Dialamatic system consists of a number of Dial Stations (FIG. 1c and 2c), one Master Timer (FIGS. 1e and 2e), one Controller (FIGS. 1d and 2d), a communications system if desired (FIGS. 1f and 2f), and one or more Punches (FIGS. 1g and 2g). Such a System is therefore a general purpose Dialamatic Time and Records Keeping System.

The Codamatic system (FIGS. 1 and 2), consists of a number of sets of Amicode cards, a number of Amicode Card Readers (Cardamatic Stations), a number of elementary Dialamatic Stations, one or more Master Timers,

one or more Controllers, one or more communications systems if desired, and one or more paper card or tape Punches.

The separate devices which make up this system may be used separately or in various combinations according to the requirements of the user. Each device may be considered as one module of a modular system. Its modular construction provides maximum system flexibility and, by making possible interchangeability of parts and Stations, is simple and economical to manufacture and maintain.

The Amicode cards and Card Reader are ideal for the storage and utilization of fixed data. The Cardamatic Time Clock is well suited for the capture of fixed data, such as an employee's number, and variable data such as the time of recording an entry of the fixed data. The Dialamatic Time Clock may be used for the capture of fixed or variable source data such as an employee's number or product quantity, respectively, and variable data such as the time. The Dialamatic System is therefore ideal for the capture and identification of variable data at its source. The Codamatic System, by virtue of its flexibility and modular construction, thus will enable the users to capture both fixed and variable data at or near its origin in a business or other system, and will automatically and immediately label (identify) and translate the captured data into machine language. The devices will refer to pertinent stored or wired-in data, and variable data recorders such as the Master Timer, will read out, translate into machine language and record elsewhere the stored or wired-in data, and will read, translate into machine language, and record elsewhere the variable data, including the date and time of the automatic operation.

(E) Original components of the Codamatic System

The words Codamatic, Cardamatic, Dialamatic and Amicode were coined by, and are believed to be original with, this claimant.

The machine instruction code, Amicode, is original with applicant, and is subtly and profoundly different from all other codes.

Amicode Cards are original with applicant and are different in principle from all other punched cards. In all other punched cards, the holes and their positions are meaningful. Desired data is punched into the card. In the Amicode cards, all data except that desired is punched out of the card. Data is carried by the remaining conducting surface, not by the holes.

The Amicode Card Reader, is original with applicant, and is different from all other Card Readers. All other punch card readers read the identical information carried by the holes in the card. The Amicode card reader does not read the holes. It reads only the conducting positions, and generates an electrical output in the standard code of which Amicode is the inverse. Further, neither the Amicode card nor the reading pole contactors move during the reading operation of the Amicode Card Reader.

The Master Timer is original with applicant. It is made by using a cam and rotary stepping switches to keep and continuously record in teletype code the time in minutes, hours and minutes, or days, hours and minutes. The encoding principle is original as far as applicant is aware.

The Controller is original with applicant. It, with its associated circuitry makes readily possible the use interchangeably of a number of Cardamatic and Dialamatic Stations, with but one Master Timer, one communications system, and one Punch as a complete (Codamatic) system.

The display and reset circuits devised by applicant for use with the Master Timer are original. The components are, however, commercially available.

The Cardamatic Time Clock is an original and revolutionary general purpose time clock. It accepts an Ami-

code card from an employee, and instead of recording only the time in human language on his card, the Cardamatic Time Clock automatically prepares a punched paper tape in teletypewriter code on which is recorded the employee's identifier (name or number), the time of the entry, the station at which he checked in or out, whether he checked in or out, and any other fixed or variable data desired, such as the number of the machine to which the employee is assigned, the temperature, and so on, ready for use directly as the input to a computer, a teletypewriter transmitter or receiver, or a Flexowriter.

The Dialamatic Time Clock is an original and revolutionary general purpose time clock. It accepts any dialled message, which may be a sequence of digits or better, for example, an employee's number, and automatically prepares a teletypewriter tape on which the number dialled, the time at which it was dialled, and any other fixed, wired-in data or variable data desired, are entered. This teletypewriter tape is ready for use directly as the input to a computer, electronic data processor, converter, a teletypewriter transmitter or receiver, or a Flexowriter.

The Controller and Master Timer are designed so that Cardamatic and Dialamatic Stations may be used interchangeably in the Codamatic System. The Controller shown will accommodate ten Stations. It may be reduced to accommodate 9, 8, 7 . . . 2 Stations, or expanded to handle any reasonable number of Stations. The Master Timer theoretically can accommodate any number of stations. However, for other reasons, it is not expected that either the Controller or one Master Timer will need to serve more than ten to twenty-five Stations. The number of Punches required is directly proportional to the number of messages to be handled per unit time by the System. As many Punches as are required may be used.

The Codamatic System is original with applicant and includes the Amicode, Amicode Cards, the Amicode Card Reader, the Cardamatic Stations and Systems, the Dialamatic Stations and Systems, the Master Timer, the Controller, the Display and Reset Circuits used with the Master Timer, and the method of storing and encoding information in teletypewriter (or other) code in stepping switches and wired-in contacts.

(F) Supplementary components of the Codamatic System

45 The five-wire line communications system is for local use, i.e., use over distances of a few thousands of feet, or less. There is nothing novel herein.

The Communications Systems used may be the commercially available teletypewriter, A. T. & T. Long Lines, 50 Western Union, or other. The teletypewriter transmitters and receivers, the Flexowriters, and the paper tape punches are standard devices commercially available. They are supplementary to the operation of the Codamatic system. No novel use is made of them, nor is such claimed.

(G) Engineering descriptions of the Modules

1. SIGNAL LAMP OPERATION

60 (a) *At the Cardamatic Stations.*—At each card reader station, there are two holding relays, and one master release relay which comprise the master control circuit. For example, at Cardamatic Station #1 (FIG. 7c), the two holding relays are RY-1*i* and RY-1*o* and the Master Release Relay is RY-R1.

When the In push button switch at Cardamatic Station #1 is actuated (manually), the path to ground is completed for the B⁺ voltage which is applied via contacts *a* and *b* of RY-R1 across the In-Use lamp and a resistor in 70 series with the In-Use lamp and holding relay, RY-1*i*, in parallel with the lamp and resistor. The In-Use lamp is turned on and the holding relay RY-1*i* will now be held in the energized position as long as the path to ground for the B⁺ voltage is closed via contacts *g* and *h* of RY-1*i* is opened and the Ready lamp thereby extinguished.

Steady B⁺ is applied from the using station to C-1 contacts (FIG. 3) as long as RY-1*i* is energized.

Upon completion of a complete reading cycle, i.e., readout of wire-in, punch card, and time, information, Master Release Relay, RY-R1, is momentarily energized, thereby breaking the B⁺ line to C-1, turning on the Ready lamp and the Wait lamp and breaking the I-I line. Relay RY-1*i* is restored to its normal position, and RY-R1 restores to its normal position as soon as the release pulse passes, thereby extinguishing the Wait lamp.

Similarly, closing of the Out push button contact momentarily, initiates the identical sequence of operations, except that the O-O line is involved instead of the I-I line (FIGS. 7b and 7c).

When any station other than 1 is in use, its Master Release Relay, RY-R1, is kept energized. The Wait lamp is on, the steady B⁺ line to RY-1*i*, via contacts *a* and *b* of RY-R1 is kept open, and Relays RY-1*i* and RY-1*o* cannot be energized; and hence, Station #1 cannot be used until the system is restored to normal by completion of the action at the In-Use station.

(b) *At Dialamatic Stations.*—While a Dialamatic Station (FIG. 8) is in its normal or ready position, a B⁺ voltage is continually present across the Ready Lamp (FIG. 8d), this voltage being applied via contacts *a* and *b* of relay, RY-1D*io*.

When the first digit of a sequence is dialled at any one of the Dialamatic Stations, for example, Dial Station #1 (FIG. 8) the "Make" contact switch, MS-1 (FIG. 8b), is closed and holds until the dial is restored to its rest or normal position. A B⁺ voltage is applied across holding relay, RY-1D*io* (FIG. 8d), thereby energizing it. As soon as it contacts *a* and *c* are closed, a steady B⁺ voltage is applied and held across RY-1D*io*, thereby holding RY-1D*io* energized until Master Release Relay, RY-RD1 (FIG. 8d), is energized.

Immediately contacts *a* and *b* of RY-1D*io* are opened, the Ready lamp is extinguished, and simultaneously, with the closing of contacts *a* and *c* of RY-1D*io*, the In-Use lamp is turned on.

When the manual dialling operation is concluded, and then Rotary Switch, RS-D1, has been advanced to its neutral position, a B⁺ voltage will be applied from H through D-1 to C-1 to disable all other Dialamatic Stations and at the same time to turn on the Wait lamps at all the other Dial Stations.

However, until the manual dialling operation is concluded, and Rotary Switch, RS-D1 (FIG. 8c), has advanced to its neutral position, another Dial Station may claim priority over Dialamatic Station #1.

In the event another Dial Station does claim priority over Dialamatic Station #1, by energizing Master Release Relay, RY-RD1, and turning on the Wait lamp at Dialamatic Station #1, the manual operator at Dialamatic Station #1 may simply wait a few seconds until the Ready lamp comes on, dial "Operator," and begin again, or, if he remembers where he left off in his dialling operation, resume as if there had been no interruption.

After the manual dialling operation is completed, and RS-D1 has advanced to its neutral position, no other Dialamatic Station can claim priority over Dialamatic Station #1, a read-out operation from Dialamatic Station #1 is ordered, the time and other data are then read-out and recorded, and the end of the complete operation is signalled by the turning off of the In-Use lamp at Dialamatic Station #1 and the Wait lamps at all other Stations, and the turning on of the Ready lamps at all Stations.

2. MASTER TIMER

(a) *Hardware.*—The Master Timer (see FIGS. 1, 2 and 4) consists of:

One (1) cam-switch which is driven at the rate of one revolution per minute (FIG. 4g).

Five (5) Rotary Switches, RS-I, II, III, IV, and V which are used to count and record time in units, tens hundreds thousands, and ten-thousands of minutes, respectively, in teletype code (FIGS. 4a, 4b, 4c, 4d, and 4e).

One (1) Rotary Switch, RS-VI (FIG. 4f) which is used to hold the record of the time in teletypewriter code, the teletypewriter symbol for "Figs" and whatever wired-in (fixed) information is desired.

10 One (1) clock-advance inhibit circuit (FIG. 4i).

One (1) holding relay, RY-HS (FIG. 4h), and

Two (2) release relays, RY-R1 (FIG. 4h) and RY-RT1 (FIG. 4i).

15 (b) *Operation.*—A commercially available cam which is driven at the rate of one revolution per minute, and which closes a contact switch once each minute, is the clock-switch device which provides one pulse (voltage-current) each minute to drive the rotary switches RS-I, RS-II, RS-III, RS-IV and RS-V which are the time recorders.

The time is measured and recorded in minutes from a reference time by the system shown in FIG. 4. The time can be as readily measured in years, days, hours and minutes,¹ or hours and minutes, as is more commonly done, or in hours and decimal fractions thereof. However, it is believed to be more convenient to measure the time in minutes for use by computers, electronic data processors, and similar devices.

20 30 Beginning at any selected reference time at which rotary switches, RS-I, RS-II, RS-III, RS-IV and RS-V are set to their zero positions, the pulses (one per minute) from the clock-switch are conducted via lines 1-1' to the motor magnet, MM-I, of Rotary Switch, RS-I (FIG. 4a).

35 After the voltage pulse is removed from MM-I, Rotary Switch, RS-I advances one position and the wiper arms touch the bank of contacts under position 1, where they remain until the second pulse passes. The Rotary Switch RS-I, wiper arms thus are advanced to positions

40 2, 3, 4, 5, 6, 7, 8, 9 and neutral in turn in 10 minutes (by ten pulses). When Rotary Switch RS-I arrives in the neutral position, B⁺ voltage is picked up from Homing Relay-I of RS-I and delivered to MM-II of Rotary Switch, RS-II (FIG. 4b). Rotary Switch, RS-II, advances from position 0 to 1 immediately after this signal B⁺ is removed.

45 Immediately upon its arrival at the neutral position, Rotary Switch, RS-I, is driven to position 0 by application of a B⁺ signal via the Homing Relay-I contact which is closed only when the RS-I is in the neutral position and the Interrupter Relay contact which is normally closed. The position 0 is the "Home" position for each of rotary switches RS-I, II, III, IV and V.

50 55 Pulses at the rate of one-per-minute from the clock switch continue to drive RS-I. For each ten times RS-I is advanced, RS-II is advanced one time. Thus RS-I counts by units, and RS-II counts by tens, of minutes. Similarly RS-III counts by hundreds, RS-IV by thousands and RS-V by ten-thousands of minutes.

60 65 Steady B⁺ voltage is connected to all contacts of Rotary Switches, RS-I, II, III, IV, V and T where indicated by the symbol. The digits 0, 1, 2, 3, 4, 5, 6, 7, 8, and 9 are here represented by teletypewriter code. Any other code may be used. However, teletypewriter

65 70 code is well-known and teletypewriter tape is widely used as a "common language" medium for mechanized records keeping and accounting operations. Contacts *a*, *b*, *c*, *d*, and *e* of the rotary switches correspond to channels 1, 2, 3, 4, and 5 of the standard teletypewriter code. Thus the digit 0 in teletypewriter code is represented by 2, 3, 5, the digit 1 is indicated by 1, 2, 3, 5, the digit 2 by 1, 2, 5, and so on as shown in the figure. Wiper arms *a*, *b*,

¹This may be done using the same techniques described in this section of description. Such a timer will be referred to hereinafter as the Alternate Master Timer.

c, d, and e of RS-I are connected to corresponding contacts of RS-VI as shown. Wiper arms *a, b, c, d, and e* of RS-II, RS-III, RS-IV, and RS-V similarly are connected to corresponding contacts of RS-T. Thus while any set of wiper arms is at rest, the teletypewriter coded representation of the position of that switch (0 to 9) is to be found in the form of B⁺ voltages in proper position on RS-T for automatic read-out.

There are 168 hours or 10080 minutes in one week. To illustrate one of the possible techniques for having the rotary switches, RS-I, II, III, IV and V reset to the zero position, let us assume that we want the master timer reset once each week. It can be reset once any chosen time interval. The principles are the same whether the time interval be one day, one week, or one year.

A steady B⁺ voltage is applied to contact 1f of Rotary Switch, RS-V. The *f* wiper arm of RS-V is connected to contact 0f of RS-IV, the *f* wiper arm of RS-IV to contact 0f of RS-III, the *f* wiper arm of RS-III to contact 7f of RS-II, the *f* wiper arm of RS-II to contact 9f of RS-I, and the *f* wiper arm of RS-I to RY-HS, a holding relay, as shown (FIG. 4). The symbol (MRS) is used to show the connection between the *f* wiper arm of RS-I and RY-HS. When these five rotary switches then are in the positions 1 0 0 7 9, the B⁺ voltage is applied to RY-HS. This is the signal used to initiate the reset operation.

The momentary energizing of RY-HS closes the normally open contact and steady B⁺ is now applied to RY-HS to hold it energized, and to ②.

② is connected to contacts *g 1, 2, 3, 4, 5, 6, 7, 8, and 9* of RS-V, to contacts *g 7, 8, and 9* of RS-II and to contact *g 9* of RS-I. The *g* wiper arms of RS-V, II, and I are connected to the corresponding interrupter relays. By virtue of the steady B⁺ voltage applied via ② rotary switches RS-I, II and V will be driven to their neutral positions, and by normal action of the B⁺ through their respective homing relays. They will be driven from their neutral to their zero positions.

When RS-V reaches its neutral position, a B⁺ voltage is connected via its homing relay, to ③ which is connected to the Release Relay, RY-RL. The Release Relay, RY-RL is energized, ground is removed from RY-HS thereby disconnecting the steady B⁺ from ②, and rotary switches RS-I, II, III, IV and V and relay RY-HS are left in normal position until B⁺ voltage is again applied through (MRS) (FIGS. 4a and 4h).

There are numerous methods by which rotary switches such as RS-I, II, III, IV and V may be reset. For example, an alternative B⁺ reset signal may be derived from the display and reset circuits as shown in FIG. 5, which is self-explanatory.

Manual resetting of rotary switches, RS-I, II, III, IV and V may be accomplished by use of the manually operated switches, S-I, S-II, S-III, S-IV and S-V in turn (FIG. 4), while observing the time as displayed on the vedor counters (FIG. 5).

The time may be displayed on vedor counters which are commercially available (FIG. 5) for use by the maintenance technician. The vedor counters are driven by rotary switch, RS-TM, which is driven by the timing pulses, one pulse per minute, from the clock-switch (FIG. 4g) via connection ⑤ shown on FIGS. 4a and 5a.

Rotary Switch, RS-T (FIG. 4f), is the store where the time and selected wired-in information is stored in teletypewriter code and from which all the data may be read-out at any time. In addition, the read-out operation does not erase the information stored. The time required for the complete read-out operation and restoration of the Master Timer to its normal position ready for another read-out operation is slightly in excess of ten (10) reading pulse times. If the reading pulses are generated at the rate of 5 per second, then 2⁺ seconds are required; if the reading pulses are generated at the

rate of 10 per second, then 1⁺ second is required, and so on.

For illustrative purposes, the "Figs" symbol, and a two digit number, 76, are wired-in at switch bank positions 1, 2 and 3. Bank positions 4, 5, 6, 7, and 8 are used for storage of the time record, the 9 position holds a blank and the 0 position, also blank, is "Home" for RS-T.

The Read-out operation is initiated by the receipt of the first reading pulse from ① (see FIGS. 4 and 3c).

10 This first pulse energizes holding and switching relay, RY-HT1 (FIG. 4i) and MM-T (FIG. 4f) of the Recording and Reading Rotary Switch, RS-T (FIG. 4f).

15 Energizing of RY-HT1 closes its normally open contacts, thereby applying steady B⁺ to its energizing coil to hold it energized, and opening the line 1—1' from the clock-switch to MM-I of RS-I. Opening the line 1—1' inhibits the clock advance while the reading operation is in progress, thus eliminating a scrambling of the message during read-out.

20 Nine more reading pulses via ① are passed to MM-T of RS-T, thereby causing RS-T to be advanced ten times, from its initial "Home" or 0 position to 1, 2, 3 . . . 9 and neutral in rapid succession.

25 When RS-T arrives at position 1, wiper arms *a, b, c, d, and e* which are connected to communications lines A, B, C, D, and E pick up the B⁺ voltages from the corresponding contacts of RS-T. For example, when RS-T is in position 1, signal voltages (B⁺) will be transferred to lines A, B, D and E (see FIG. 4j), when RS-T is in position 2, signal voltages will be transferred to lines A, B, and C, and when RS-T is in position 3 to A, C, and E. Assume the time at this particular instant to be 02538 minutes (42 hours and 18 minutes, or one day, 18 hours and 18 minutes) from reference time. Signal 30 voltages will be transferred

	when RS-T is in position:	to lines:
4		B, C, and E,
5		A, B, and E,
6		E,
7		A,
8		B and C, but

when RS-T is in position 9, no voltages will be transferred as the position is left blank. Wired-in information, of course, may be stored at position 9. If one wished to count time in hundreds of thousands of minutes by addition of a rotary switch driven by RS-V just as RS-V is driven by RS-IV, then position 9 may be used as the store for the hundreds-of-thousands-of-minutes digit indicator.

If a 5 wire-communications line is used, then the lines A, B, C, D, and E are connected directly to A', B', C', D', and E' respectively (FIG. 4j), and A', B', C', D', and E' are connected directly to the corresponding punch actuator terminals A'', B'', C'', D'', and E'' (FIG. 4k).

60 If a one (1) wire communication line is used, then a parallel-to-serial-device and a serial-to-parallel device are required in the communications system, at the input and output ends respectively. These are commercially available or may be constructed simply with relays by application of standard engineering techniques.

65 As the punch-actuator (FIG. 4k) is driven, holes are punched in the 5-channel paper tape (FIG. 4l) to reproduce the message read.

66 When RS-T is driven to its neutral position, a B⁺ signal is transferred through the normally open Homing Switch contact (which is closed only when RS-T is in its neutral position) of RS-T to the Interrupter Relay of RS-T thereby driving (through MM-T) RS-T from its neutral 70 to its zero or "Home" position.

67 Simultaneously, a B⁺ signal is delivered to ④ to energize RY-RT1 (FIG. 4i) thereby breaking the steady B⁺ line to RY-HT1 (FIG. 4i), returning RY-HT1 to its normal position, and closing the lines 1—1' (FIG. 4) 75 so that the clock may now advance. The Master Timer

is now in normal condition, ready for another read-out operation.

(c) *An Alternate Master Timer*.—The Alternate Master Timer shown (FIG. 9) is an electromechanical calendar-clock which counts time by year, day, hour and minute in teletype code.

The year may be identified without ambiguity by its last two digits until the end of this century. Thus, 1956 may be recorded as 56, 1965 as 65, and so on. The first two digits, 19, which identify the century will remain unchanged until the year 2000. Therefore, the last two digits of the year are used to identify the year.

Instead of using months and days of the month, the days of the year will be numbered from 1 to 366. This will avoid use of additional circuitry needed to count different numbers of days in the various months, as for example, February, March, and April. Once each year on the 365th day of the year except in leap years, the maintenance technician will have to advance the Alternate Master Timer one day. In leap years, he will not have to change the setting of the Timer.

The hours of a day are numbered simply from 00 to 23, and minutes are counted from 00 to 59.

The same techniques as are used in the design of the Master Timer which counts and records only in minutes (FIG. 4) may be used directly in the design of the Alternate Master Timer illustrated (FIG. 9), or any other alternate Timer.

All digits will be recorded in teletypewriter code and all outputs for machine use will be in teletypewriter code. Visual display and automatic Timer reset circuits may be readily designed for the Alternate Master Timers by use of the same techniques described in section I. (G) 2. (b).

Provision may be made for manual reset of all rotary switches in the Alternate Master Timer by use of the same techniques as are used to manually reset the Master Timer described in section I. (G) 2. (b).

3. THE CONTROLLER

(a) *Hardware*.—The Controller (FIG. 3) consists of:

The Searcher (FIG. 3a) which is Rotary Searching Switch #1. Rotary Searching Switch #1 has eleven levels and ten banks of contacts plus the neutral bank to which the wiper arms are connected. It may actually be two rotary switches each with ten banks of contacts plus the neutral bank, but with only six and five levels respectively, driven in parallel and connected as shown in FIG. 3a, as if they were one big rotary switch.

The Traffic Manager (FIG. 3b), which consists of ten separate relays, RY-M1, RY-M2, RY-M3, RY-M4, RY-M5, RY-M6, RY-M7, RY-M8, RY-M9, and RY-M10.

One (1) Holding Relay, RY-H1 (FIG. 3d)

A Reading Pulses Generator (FIGS. 3e and 3f)

The Records Keeper (FIG. 3c) which is made up of two counting rotary switches, RK-1 and RK-2, two holding relays, RY-H2 and RY-H3, and ten release relays remotely located, one at each of the Dial and Card Reader stations.

(b) *Operation*.—When the In or Out push button switch at any Cardamatic station, or the In or Out symbol is dialled at any Dialamatic Station, a B⁺ voltage is momentarily applied to one of the contacts C-1, C-2, C-3, C-4 . . . C-10, corresponding to the number of the Cardamatic or Dialamatic Station in use. Assume that the In push-button of Cardamatic Station #1 is actuated, in order that the sequence of operations may be illustrated.

Actuation of the In push-button closes the steady B⁺ line from the using station to the contacts marked C-1 (FIGS. 3a and 3b).

Application of B⁺ to C-1 energizes relay RY-M1 (FIG. 3b) closing its normally open contact, thereby delivering reading pulses through a normally closed contact of Holding Relay, RY-H1 (FIG. 3d) to the motor mag-

70
75

net, MM-S1 of Rotary Switch, RS-S, "The Searcher" (FIG. 3a). Rotary Switch, RS-S, advances once immediately after the first reading pulse has passed, and continues to advance, one step at a time, with the passage of each successive reading pulse, until B⁺ voltage is found by its k wiper arm.

Application of B⁺ to C-1 also connects the steady B⁺ from the using station to RS-S contact k in bank 10, and to contacts a, b, c, d, e, f, g, h, i and j in bank 1.

10 As soon as wiper arm k finds B⁺ in bank 10, RY-H1 is energized, and thereby the normally open contacts of RY-H1 are closed, breaking the reading pulses path through one set of its contacts. Rotary Switch RS-S, advances one position to its neutral position. Immediately, 15 a B⁺ voltage is applied to the Interrupter Relay of RS-S from the Homing Relay, to drive RS-S to its 1 position. RS-S will now remain in its 1 position until the Master Release Relay, RY-CR1 is energized.

While RS-S is in its 1 position, B⁺ voltage is applied 20 to the release relays in stations 2, 3, 4, 5, 6, 7, 8 and 9, and they are energized. (Similarly when RS-S is in its 2 position, the release relays in stations 1, 3, 5, 6, 7, 8, and 9 are energized and so on.) (FIG. 3a.) In this manner only one using station at a time is permitted to operate.

25 As soon as Holding Relay, RY-H1 is energized, the reading pulses which were being passed through its contacts a and b to MM-S1 are diverted through contacts a and c to Records Keeper Relay RY-H2, contact d, thence through contact e to MM-RK1 and via contacts 30 g and h of RY-H2 to the connection P to be delivered to the Station in use, in this example, Cardamatic Station #1 (FIG. 7).

Ten reading pulses will be passed via contacts g and h 35 of RY-H2 to Cardamatic Station #1. When the 10th pulse has passed, rotary switch RK-1 will be driven to its neutral position, at which time B⁺ from its Homing Relay normally open, but now closed contact, will be applied to the Interrupter Relay of RK-1 to drive RK-1 to "Home" in the 0 position. The same B⁺ will simultaneously energize relay RY-H2. As soon as RY-H2 is energized, the reading pulses are diverted from Card Reader Station #1 and routed to the motor magnet, MM-RK2, and to Holding Relay, RY-H3 via contacts g and i or RY-H2 and to the Master Timer (FIG. 4) 40 via contacts g and i or RY-H2 and contacts d and f of RY-H3.

Ten reading pulses will be passed to the Master Timer. When the 10th pulse has passed, Rotary Switch, RK-2 50 will advance to its neutral position, at which time B⁺ voltage will be applied from its Homing Relay to its Interrupter Relay, and to the conductor terminals marked RL. Application of B⁺ to the Interrupter Relay drives RK-2 from neutral to its "Home" or 0 position. Application of B⁺ to the conductor terminals indicated by 55 RL energizes all the release relays connected to RL, as shown on the various figures, thereby returning all stations to the ready or normal position.

To illustrate the principles of operation, blocks of 10 pulses have been used. However, the principles of design permit one to "gate" any desired number of pulses to each Cardamatic Station, Dialamatic Station, and the Master Timer.

4. THE CARDAMATIC SYSTEM

65 (a) *General*.—The Amicode Card Reader when connected (via short or long communications lines) to an electro-mechanical punch accepts a Amicode punched card or tape and produces as an output a punched paper tape or card in the code inverse to that on the Amicode card, and such other additional wired-in information as is desired, for example, card reader station identification, and such other variable information as one may choose to order read-out from other devices, as for instance, the time at which the card is read.

(b) *Amicode*.—Commercially available punched cards

are coded such that the position of any punched hole is meaningful, and each hole carries information. Codes commonly used are the five-channel (teletypewriter), and six-, seven- and eight-channel which are used in various commercially available devices such as digital computers.

Amicode is original with this claimant and is subtly and profoundly different from all other codes, either existing or yet to be devised. For example, in the standard teletypewriter code, punched paper tape or cards to represent the sequence of characters (or message) "Figs." 3, 5, 3, 6, 8, 9, 4, 7 would have holes punched as shown in FIG. 6b. But the Amicode coded punched paper tape or cards to carry the same message and to be used in the Amicode card or tape reader would have holes punched as shown in FIG. 6a. The holes do not carry the desired information. The information is carried in the positions not punched. This is completely different from all other punched card and punched tape systems commercially available.

The electrical signals produced at the output of the Amicode Card Reader, by the ordered reading operation will, upon application to the appropriate punch, produce punched cards or tapes in the inverse of the code punched on the Amicode card. Thus, for example, if a five channel code which is the opposite of teletypewriter code is punched onto an Amicode card, and this Amicode card is then inserted in the Amicode Card Reader and read-out, the output of the Amicode Card Reader will be standard teletypewriter signals which may be used to drive an ordinary teletypewriter or Flexowriter punch to produce teletypewriter punched tape and/or typed information carried by the teletypewriter message signals.

To illustrate the principle, teletypewriter code punched paper tape output is presumed desired. An original code, which is the universe of the teletypewriter code, is used on the Amicode punched card and the Amicode Card Reader is designed to read the Card and produce standard teletypewriter coded output signals (FIGS. 6a and 6b).

(c) *The Amicode card and Amicode card reader.*—The Amicode card or tape (FIGS. 6a and 6i) may be made of thick or thin electrically conducting metal, for example, aluminum, copper, etc., or plastic, paper or cardboard coated with a thin layer of conducting material such as graphite, aluminum, copper, etc. The size, i.e. width and length may be whatever is most convenient. A good convenient size for the mirror-image teletypewriter-coded card or tape is about 2 to 3 inches in width and 5 to 8 inches in length. The tentative dimensions suggested are convenient for filing for easy visual and manual removal from, and replacement in, card or tape files, or a person's pocket.

Viewed externally, the Amicode card reader is a box-like container (FIGS. 6e, 6f, 6g and 6h). It may have an opening at the top (FIG. 6c) or a slot in the front (FIG. 6f) for insertion of the mirror image card. It has two push-button momentary contact switches (labelled In and Out in the demonstration model) mounted on the top as shown (FIGS. 6e, 6f, 6g and 6h). Mounted on the front (FIG. 6f) are three signal lamps, and on the rear a power-on switch, a power-on indicator lamp, if desired, and a lead-through opening for the power connector lead.

The complete Amicode card reader consists of the container, a number of momentary-contact-push-button switches (two are shown) a slot or other opening for insertion of the Amicode card, signal lamps (front and rear) and power on-off switch, all visible (see paragraph above). In addition, inside the container are to be found the Card Reader pole contactors (FIG. 6c or FIG. 6j), the master control relays and circuits (FIG. 7c), a card reading rotary switch, RS-CR1 (FIG. 7a) with electrical wiring between it and appropriate pole contactors (FIGS.

5 6j and 7b), and optionally with the user, a local source of B⁺ voltage and current (FIG. 7g).

This is the simplest electro-mechanical card reader ever devised. The number of moving parts is a minimum. The card is not moved while it is being read, nor do the card reader pole contactors (FIGS. 6c or 6j) do not move while the card is being read.

There is but one correct position in the card reader for any card, and the card reading operation cannot be initiated unless the card is in the correct position. This is provided for by a very simple expedient. The In or Out momentary-contact push-button switch electrical contact can only be made through the corresponding hole of the Amicode card (FIGS. 6a, 6f, and 6h). The In and Out switches are simply located asymmetrically as shown in the figures so that neither switch can be closed unless the card is right side up and right end to.

(d) *Operation of the Cardamatic System.*—An Amicode coded punched card (or tape) is placed in contact 10 with the pole or spring card contactors of the Amicode Card Reader (FIGS. 6i and 6j or FIGS. 6a and 6c) by simply inserting the card in the card slot or other opening (FIGS. 6e, 6f, 6g and 6h) in its only correct position, and pushing a momentary-contact start button switch. 15 Two alternate start buttons are shown in the demonstration model (FIGS. 6c, 6f, 6g and 6h).

The operator chooses either the In or Out start button, whichever is appropriate, and pushes it down, thereby momentarily closing the line 1—1' or m—m' (FIG. 7c) 20 and energizing relay, RY-1i or RY-1o, depending upon whether he pushed the In or Out push-button switch. The In or Out start button switch is restored to its normal position by light spring action immediately the operator releases his pressure upon the button.

To illustrate the ensuing sequence of events, let us assume that the operator momentarily closes push button switch In. The entire operation will proceed smoothly whether he holds the switch closed or releases it promptly.

When the momentary-contact-start-switch, In, is closed, 25 relay RY-1i (FIG. 7c) is energized, due to the closure of line 1—1'. The closing of line 1—1' connects B⁺ from contacts a and b of RY-R1 to RY-1i in parallel with the In-Use lamp in series with a suitable resistor, R. Immediately, RY-1i is energized, its a contact "breaks" from b and "makes" with c, its d contact "breaks" from e and "makes" with f, and its g contact "breaks" from h and "makes" with i. Thus, line I—I (FIGS. 7b and 7c) is closed, B⁺ is applied to C-1 (FIGS. 7c, 3a and 3b) thereby energizing the Controller (FIG. 3), the Ready Lamp at Amicode Card-Reader Station #1 is turned off, the In-Use Lamp at Amicode Card Reader Station #1 is turned on, the Wait Lamps at all other stations are turned on (via the Controller) and all other stations are disabled (via the Controller) 30 while Amicode Card Reader Station #1 is in use.

Similarly, when any of the other Card Reader Stations is in use, its In-Use lamp will be on, its Ready lamp off, and all stations except the one in use will be disabled with their Wait lamps on (FIG. 9).

35 The steady B⁺ (FIG. 7a) is connected to C-1 via contacts d and f of RY-1i (FIG. 7c) and thus to a bare portion of the Amicode card which is in position to be read (FIG. 7b), to the Traffic Manager (FIG. 3b) and to the Searcher, RS-S, (FIG. 3a).

40 Application of B⁺ to RY-M1 (FIG. 3b) energizes RY-M1, causing its contacts a and b to "make," thereby passing reading pulses (FIG. 3e) to MM-S1 via contacts a and b of RY-H1 (FIG. 3d), and stepping rotary switch RS-S (the Searcher) until it finds the B⁺ which is applied from C-1 to a selected set of its contacts (FIG. 3a) according to the identification of the using station. Upon arrival of wiper arm k of RS-S to the k contact of RS-S where B⁺ is to be found, relay RY-H1 (FIG. 3d) is energized. Contacts a and b and c and e of RY-H1 45 "break," and contacts a and c and d and f of RY-H1

"make." The Searcher advances to its next position and stops since no further reading pulses are applied to MM-S1.

A steady B+ is applied to RY-H1 via its contacts, d and f, to hold it energized until such time as the master release relay, RY-CR1 (FIG. 3d) is energized.

Also, reading pulses are now routed via contacts a and c of RY-H1 (FIG. 3d) to RK, and thus to MM-RK1 of the Records Keeper (FIG. 3c) via contacts d and e of RY-H2 and to P (FIG. 7a). Rotary Switch, RK-1, will be stepped from its "Home" position ten times to its neutral position. Upon arrival at its neutral position a B+ voltage will be applied through the normally open contacts of RK-1's Homing Switch to its Interrupter Relay, to advance RK-1 to its "Home" position. When RK-1 arrives in its neutral position, B+ from its Homing Switch is also momentarily applied to Holding Relay, RY-H2, energizing it, and "breaking" its contacts a and b, d and e, and g and h, thereby disconnecting the reading pulses (from RK) from MM-RK1, and routing them to MM-RK2 of Rotary Switch, RK-2, via contacts g and i of RY-H2. When contacts g and h of RK-2 are "broken," the reading pulses to P are discontinued. Thus Rotary Switch, RK-1 in conjunction with RY-H2 has served as a records keeper, counting and allowing exactly 10 reading pulses to pass to P (FIG. 7a).

The application of 10 reading pulses to P (FIG. 7a) drives the Card Reader Rotary Switch, RS-CR1, from its "Home" (Neutral) position in ten steps to its #10 position. Wiper arms a, b, c, d, and e of RS-CR1 pick up voltages from each bank of contacts corresponding to the information wired-in or carried by the Amicode card, in teletypewriter code. Thus, as illustrated in the diagram, from the first reading position (the #1 bank of contacts), wiper arms a, b, d, and e would pick up B+ corresponding to the teletype 5-channel signal "Figs." In the next reading position, since line I—I is closed (by RY-1i, FIG. 7c), wiper arm a will pick up B+ corresponding to the teletypewriter code signal for 3 which is here interpreted, by virtue of its position in the sequence of characters in the message, to represent "In" or "Begin." In the fourth, fifth, sixth, seventh, eighth and ninth positions, B+ will be picked up by wiper arms, a, b, c, d, e, according to the decimal digit originally encoded on the Amicode card. In the tenth position, a card reader station identification number may be wired-in, if desired, or the position may be left unwired and thus blank. There is no theoretical limit to the length of card or the amount of information which may be carried by the Amicode card or wired-in in the Card Reader. Up to 50 characters in a message is simple, since stepping switches of 50 banks of contacts each are readily available commercially. Greater lengths of messages may be handled by connecting stepping switches in series to operate electrically as if they were one long stepping switch.

When the Card Reading Rotary Switch, RS-CR1 arrives in its #10 position (driven there by the reading pulses applied to P), normally open contacts a and c of its Homing Switch "make" and normally closed contacts a and b of its Homing Switch "break." A B+ voltage is thereby applied to MM-C1 to advance RS-CR1 to its neutral ("Home") position. Upon arrival in its neutral position, normally closed contacts a and b of its Homing Switch are again closed and its normally open contacts a and c are restored to their open condition. Card Reading Rotary Switch, RS-CR1 now resets in its "Home" position. The Card Reading operation is complete.

However, the time at which the card is read and other information may be needed. Provision is made for reading and recording the time in minutes, in hours and minutes, or this being preferable where the data is to be used by a digital computer or some other electronic data processing equipment. It could as readily be arranged to record the time in years, days of the year, hours and minutes as shown in FIG. 9 which is self-explanatory.

Recalling now that when RY-H2 is energized, its contacts g and i, are "made," and reading pulses from RK are now routed to MM-RK2 of Rotary Switch RK-2. These reading pulses drive RK-2 through ten consecutive positions, from its "Home" to its neutral position, while simultaneously, ten reading pulses are routed to T (FIG. 3c and FIG. 4).

The reading pulses routed to T via contacts d and f of RY-H3 are also applied to holding relay, RY-H3. The first reading pulse energizes RY-H3 but until its contacts d and f are closed, the parallel reading pulse cannot get to T. Therefore it is necessary that the time-duration of the reading pulses be somewhat greater than the "make" time of RY-H3. The time duration, i.e. the "width," of the reading pulses is equal to the length of time contacts a and b of contact switch CS-1 (FIG. 3f) are closed, which can be regulated by the dimensions of the raised portion (r) of W-1 (FIG. 3f). Once RY-H3 is energized, it holds by virtue of the B+ applied through its own contacts a and c.

After the first reading pulse passes MM-RK2 (FIG. 8c), Rotary Switch, RK-2 is stepped one position from "Home." After the second pulse has passed, RK-2 is advanced to its #2 position, and so on, until after the tenth pulse passes, RK-2 is advanced to its tenth or neutral position. Upon the arrival of RK-2 in its neutral position, the normally open contact of its Homing Switch closes, thereby passing B+ to its Interrupter Relay (causing RK-2 to advance to its "Home" position), and to RL. Application of B+ to RL energizes all release relays thereby removing B+ from all C-1 lines and restoring all relays except the release relays to normal. And as soon as RK-2 leaves its neutral position stepping toward its "Home" position, its normally open contact opens thereby removing B+ from the Release Relays thus restoring them to normal. The action of all the relays is sufficiently fast compared to the rate of generation of the reading pulses that only ten reading pulses are delivered to T before relay RL-H3 is restored to normal.

The delivery of ten reading pulses to T is adequate to insure operation of the Master Timer through one complete cycle, as described in section I.(G) 2 of this description.

5. THE DIALAMATIC SYSTEM

(a) *Hardware.*—Each Dialamatic Station (FIG. 8) consists of:

- Three signal lamps (Ready, In-Use and Wait) (FIG. 8a)
- One Dial and associated circuitry (FIG. 8b),
- One Traffic Routing Rotary Switch, RS-D1 (FIG. 8c),
- One Dial Control and Release Circuit comprising one master control relay and one master release relay (FIG. 8d)
- One set of Dial Message Recorders comprising one to nine rotary stepping switches (FIGS. 8e and 8g). For illustrative purposes, seven such switches are shown, RS-D2, RS-D3, RS-D4, RS-D5, RS-D6, RS-D7, and RS-D8
- One Dial Message Store, Rotary Switch, RS-D9 (FIG. 8f)
- One Time Delay Relay, RY-DD1 (FIG. 8g)
- One Counting Switch, RS-D10 (FIG. 8k)
- Five connectors to the communications system (FIGS. 8f and 8h)
- One "Go" push-button switch (FIG. 8k)

(b) *Normal operation of a Dialamatic station.*—(1) Operation of a Dialamatic station is initiated immediately any digit is dialled. The "Make" contact switch, MS-1 (FIG. 8b), is closed as soon as a dialling action is started and remains closed until the dialling of the first selected digit is complete. Each time a digit is dialled the Make contact is closed at the beginning of the dialling operation and remains closed until the dialling action is completed.

75 The first digit dialled can be selected to mean, by vir-

tue of its position in the sequence of numbers dialled, to a computer or human, Start, Stop, In, Out, Begin, End, etc., whatever one desires. In the example chosen, the digit 3 when dialled first means In or Start and the digit 5 when dialled first in the sequence means Out or Stop. The next sequence of digits dialled, say six, for example, may comprise an identification number assigned to an employee, an order number, a process, machine, or so forth. Any of the digits 1, 2, 3, 4, 5, 6, 7, 8 or 9 may be dialled at any time. The digit "0" is excluded, being reserved to mean "Mistake" whenever it is dialled.

When the Make contact closes for the first time, steady B⁺ voltage is applied across motor magnet, MM-D1, of the traffic routing rotary switch, RS-D1, the master control relay, RY-1Dio and the In-Use lamp in series with a suitable resistor. Relay RY-1Dio is thereby energized, and a steady B⁺ is connected through its contacts *a* and *c* across itself thus holding it energized until such time and the Master Release Relay, RY-RD1 is energized. Also when RY-1Dio is energized, the Ready lamp is extinguished (contacts *a* and *b* are separated) and the In-Use lamp is turned on (since contacts *a* and *c* are connected).

Line L—L' which is connected to wiper arm *a* or RS-D1, is broken (opened) a number of times equal to the value of the digit dialled by the interrupter switch, IS-1. For example, for the "In" symbol, the line L—L' is broken three times, for the "Out" symbol, five times, for the digit nine, nine times and so forth.

When the first digit is dialled, RS-D1 is in its "Home" position which is the #1 bank position (FIG. 8c). Thus the interrupter switch signals are routed through RS-D1 wiper arm *a*, to the #1 *a* contact and directly to Dial Message Recorder, RS-D2, which is driven to a position corresponding to the digit dialled.

As soon as the B⁺ signal is removed from MM-D1 of RS-D1, which occurs at the termination of the dialling action, MM-D1 advances RS-D1 to its next sequential position. Thus, as soon as the first signal digit has been dialled, B⁺ is removed from MM-D1 and RS-D1 advances to its #2 bank position, ready to receive the next (second) dialled digit. The interrupter switch signals along line L—L' will now be passed via contact 2*a* and wiper arm *a* or RS-D1 to Dial Message Recorder, RS-D3. After the second digit has been dialled, RS-D1 will be advanced to its #3 position, etc. and each successive digit dialled will thus be routed correctly to its corresponding Dial Message Recorder, until there is a digit stored in each of the Dial Message Recorders, RS-D2, 3, 4, 5, 6, 7, and 8.

After dialling the code signal digit, for example, the In, Start, Out, or Stop and a six digit number, the dialler stops. Signal digit, after the seventh digit has been dialled, RS-D1 advances to its #8 position, where it comes to rest and remains until the dialler pushes the Go push-button switch (FIG. 8k). The closing of the Go push-button switch connects B⁺ to contact 8*b* of Rotary Switch, RS-D1, where it is picked up by wiper arm *b* of RS-D1 and connected to its own interrupter relay. This causes RS-D1 to be advanced to its #9 position where B⁺ is again picked up by its wiper arm *b* and the advance action repeated, and RS-D1 is advanced to its neutral position. Upon the arrival of RS-D1 in its neutral position, B⁺ is connected via its Homing Relay to its interrupter relay and RS-D1 is thereby advanced to its "Home" or #1 position where it rests until a further sequence of operations transpires finally resulting in the activation of Master Release Relay, RY-RD1 (FIG. 8d).

Use of the Go switch allows the dialler time to determine that he has made a mistake, if he has done so, and to correct his error by dialling "Operator" or "0" ("Mistake") after the seven digit sequence has been dialled.

Also, when RS-D1 arrives in its neutral position, steady B⁺ from the *a* and *c* contacts of Time Delay Relay, RY-DD1 (FIG. 8g) is passed via the Homing Relay of

RS-D1 to Holding Relay, RY-DH1 (FIG. 8k) which is energized thereby.

As soon as RY-DH1 is energized, steady B⁺ is delivered to C-1, and the Traffic Manager (FIG. 3b) and the Searcher (FIG. 3a) circuits in the Controller are activated. The sequence of events is now governed by the Controller as explained in section 3 of this description, and the time of dialling and other data are read-out and recorded on the teletypewriter tape to complete the operation.

All other stations are now disabled, and the Wait lamps are turned on at all other stations, until the reading action is completed.

Ten reading pulses will be delivered to the motor magnet, MM-D9, of Rotary Switch, RS-D9, the Dial Message Store, to drive RS-D9 through ten successive positions, from its Home (Neutral) position to its #10 position. Outputs will be delivered from each successive position of RS-D9 via the wiper arms, *a*, *b*, *c*, *d*, and *e*, of RS-D9 to corresponding connectors of the communications system (FIG. 8h). A coded signal (shown in the teletypewriter symbol "Figs") will be first read (FIG. 8j), then the "In" or "Out" symbol, which ever was dialled, then the six digit number which was dialled, then the dial station identification number and/or other wired-in information as desired. To illustrate the principle, it is assumed that the dialler has dialled "In" and the six digit number 368 947, that the dial station number is 1 and no other information is wired-in. The corresponding output would be punched on teletypewriter 5-channel punched paper tape as shown in FIG. 8j.

Upon arrival in its #10 position, RS-D9 comes to rest temporarily and a B⁺ voltage is delivered from wiper arm *f* of RS-D9 to contact 10*f* which is connected to the Q contacts (FIG. 8g). The Q contacts (FIG. 8g) are connected to the Homing switches and Interrupter Relays of the Dial Message Recorders (FIG. 8e) as shown in the Detail (FIG. 8g) so that each of rotary switches RS-D2, RS-D3, RS-D4, RS-D5, RS-D6, RS-D7, and RS-D8 are driven to their neutral positions by the steady B⁺ delivered through the Q contacts.

Upon arrival at the "0" bank position, any one of the Dial Message Recorders, RS-D2, RS-D3, RS-D4, RS-D5, RS-D6, RS-D7, and RS-D8, picks up a B⁺ voltage on its wiper arm *f* from its contact "0" *f*. This voltage is applied to and energizes Time Delay Relay, RY-DD1 (FIG. 8g). Contacts *a* and *b* of RY-DD1 are brought into contact and a steady B⁺ voltage applied via contacts *a* and *b* to the Q contacts. Each of the Dial Message Recorder Homing Switches is set so that its contacts *a* and *b* are separated as the Dial Message Recorder Rotary Switch leaves the #10 position and approaches the neutral position, and the Homing Switch is open when the Dial Message Recorder is in its neutral position. Thus B⁺ is disconnected from the Interrupter Relays of each of the Dial Message Recorder rotary switches when the Dial Message Recorder rotary switch arrives in its neutral position. These reset actions are completed before arrival of the master release signal from RL (FIG. 3c) to RL (FIGS. 8d and 8f). Upon arrival of the B⁺ release signal at RL (FIG. 8f), Rotary Switch, RS-D9, the Dial Message Store, is advanced one position from its #10 position to its neutral position which for it is "Home." The Q contacts now have the B⁺ from RS-D9, contact 10*f* removed from them, but will have B⁺ from the Time Delay Relay, RY-DD1, via its contacts *a* and *b*, until the Time Delay Relay, RY-DD1 returns to normal.

RY-DD1 is set to hold for a holding time slightly greater than is adequate for resetting all the rotary switches at the Dial Stations. The time is short, however, a few seconds at most since the reading pulse rate is between 5 and 20 pulses per second.

(c) The "Mistake" correction operation.—Now suppose that at any time in the dialling operation, the dialler, for

any reason, dials "Mistake" or "Operator" ("0"). The following sequence of events transpires. Wiper arm *f* of one of the Rotary Switches RS-D2 to RS-D8, inclusive will pick up B⁺ voltage from its "0" *f* contact, and deliver it via the M contacts, all of which are connected in parallel, to the Time Delay Relay, RY-DD1 (FIG. 8g), thereby energizing RY-DD1. A steady B⁺ voltage is now delivered via contacts *a* and *b* of RY-DD1 to the Homing Switches and Interrupter Relays of the Dial Message Recorders (FIGS. 8e and 8g) so that each of rotary switches RS-D2 to RS-D8, inclusive, are driven in turn to their neutral positions, as described immediately above. Shortly after these reset actions are completed, the Time Delay Relay, RY-DD1, returns to normal.

Rotary Switch, RS-D1, is reset by the application of B⁺ to its *k* contacts via contacts *a* and *b* of RY-DD1.

Upon arrival of RS-D1 in its neutral position, B⁺ is normally delivered to the Interrupter Relay of RS-D1 via the normally open contact of its Homing Relay and RS-D1 is thereby driven to its #1 position. A read-out order signal is also normally delivered to D-1 thence to C-1, and a read-out operation takes place.

However, when a Mistake order has been dialled, the read-out operation is unnecessary, and is to be avoided. To prevent the occurrence of a normal read-out operation after the operator dials Mistake, the steady B⁺ line through contacts *a* and *c* of RY-DD1 to the Homing Switch of RS-D1 is held open while RY-DD1 is energized. Thus RS-D1 may be reset without initiation of the read-out operation.

In summary, if at any time during the dialling operation, the operator wishes to correct an actual or imaginary mistake and "erase" the message he has dialled, he may do so by dialling "Mistake."

Now suppose, for example, he has just completed dialling "In" and a six digit number and suddenly realizes he has made an error. He may now dial Operator ("Mistake") to correct his error. In this case, Counting Switch, RS-D10 (FIG. 8k), which normally remains in the neutral position is advanced by virtue of the voltage from the Interrupter Switch, IS-1, in line L-L' applied to motor magnet, MM-D10, of RS-D10, via wiper arm *a* and contact 8a of RS-D1 (contacts labelled E in the figure) where normally no voltage is delivered. Immediately RS-D10 advances one position, B⁺ is picked up by its wiper arm *a* and delivered to M to initiate the "erasing" action described above. The result will be to have the message wiped out, the read-out action deferred, and all Dial Message Recorders, RS-D2 to RS-D8, inclusive, RS-D1 and RS-D10 reset to their normal positions.

In the normal sequence, no voltage is picked up by wiper arm *a* from contact 8a of RS-D1 and Counting Switch, RS-D10, is not advanced.

II. SOME APPLICATIONS OF THE CODAMATIC SYSTEM

(A) Capture of payroll source data

In the business world generally today, there are two methods in general use for accounting for time spent on the job by the hourly worker.

(1) The hourly worker punches a time clock whenever he begins or ends a working period. On his "time-card" is printed a date and time corresponding to each punch-in or punch-out operation. The source data is in human language, not in machine language.

In order to get the source data from the time-card file or the timekeeper's listings into machine language, it is necessary that a keyboard-operator transcribe the information from the files and/or listings into punch cards, magnetic cards, magnetic tape or punched paper tape.

(2) A clerk ("timekeeper") keeps a manual record of the number and kind (regular, overtime, premium, etc.) of hours worked by each employee during a pay period. The timekeeper's records contain all the source data

needed for preparation of the payroll. But the data is in human, *not* machine language.

With the Cardamatic Time Clock or the Dialamatic Time Clock, all the source data on hourly workers may be automatically captured at its origin in machine language as a by-product of the normal check-in and check-out operations of the workers.

(B) Capture of source data for costing of certain operations

For complete costing of operations, by-product, it is necessary that data be collected on material, personnel, facilities (such as production machines) and time used in the production operations, as well as such items as the initial costs of material, and so on.

There are a great many techniques and devices originally developed for telemetering applications which could be used directly or with slight modifications to capture data on material, such as its weight or volume, or number of pieces moving past a designated point.

The Codamatic System with its kinds of input Stations, the Cardamatic and Dialamatic can be used for the capture of the required fixed and variable data. To illustrate:

(1) The machine or station number, and other static data, can be recorded on a punched card or paper tape or "wired-in" at a Cardamatic or Dialamatic Station. By establishment of a regular format, and proper training and motivation of the worker, all data may be captured at the work station, translated into machine language in the form of punched paper tape, punch cards or magnetic tape or, for instance, ready for use directly as the input to a data processor.

When the work or manufacturing instructions (on hard copy) and material arrive at a machine station, the worker first dials one symbol which indicates beginning of an operation. He then inserts his identifier (employee number) card or tape into the Amicode card Reader. He next dials the manufacturing order number. Then he dials the quantity (number of pieces, weight, etc.) of material received, and the material identifier (a product number), or punches a button to have it recorded automatically.

When the worker completes his operations upon the material, he dials a symbol indicating end of operation, inserts his identifier into the reader, dials the quantity of material passed on to the next station, and the material identifier (same product number as above).

In both these instances described above, the Cardamatic and Dialamatic Stations of the Codamatic system would accept all of the data and record it, the date and time and such other wired-in data as desired, such as, for example, sentinels for use of a teletypewriter, converter or computer in machine language at the site of a data processor.

(C) Telephone message length recorder and records keeper

A Dialamatic System, without dials, can be installed with minor modifications in a central telephone exchange, and there keep records (in teletypewriter code on punched paper tape ready for computer or other data processor use) on the dates, times and lengths of messages by user dial station.

(D) Recording of bank deposits and withdrawals

With slight modifications, the Codamatic system can be used for a completely mechanized records keeping and accounting system by banks.

Each Depositor with a particular bank can have issued to him one individual Amicode Card. At each Paying and Receiving Bank Teller's Station there could be one Amicode Card Reader and one Dialmatic Station. Centrally located in the Bank could be one Master Timer, one Controller, one Punch and one data processor such

as the Univac File Computer or an IBM 650. Now, to make a deposit, the customer would fill out the usual deposit slip (for his own use, primarily) and hand it, along with his Amicode card and deposit, to the teller. The teller, after verifying the amount received, could simply insert the Amicode card into the Card Reader, push the start-button switch meaning "In" or "Deposit" (were it a withdrawal, the teller could push the other start-button switch meaning "Out" or "Withdrawal"), dial the amount in dollars and cents, and a sentinel meaning end of transaction. Recorded at the site of the Bank's Data Processor by the Punch, would be the date and time of the transaction, the kind of transaction, the Teller's number, the customer's account number, and the amount of the transaction, all in machine language.

(E) *Fast tape handling*

Use of the inverse teletypewriter code, one of the innumerable possible Amicodes, make possible the design and construction of a much faster punched tape reader than now exists.

The Amicode inverse teletypewriter code tape can be read automatically faster than any other punched paper tape, due to the facts that conducting surface positions are read. The tape need not be started and stopped momentarily as it is being read as is done in the mechanical handling of all other punched tapes, but can be driven continuously as fast as is possible. The only limitation upon the speed of automatically reading of the Amicode inverse teletypewriter code is the speed of operation of the electronics circuits.

The Amicode teletypewriter coded tapes can be prepared (punched) at the same rates as ordinary punched paper tapes.

The Amicode inverse teletypewriter code tape actually need not be punched. It is only necessary that there be a conducting surface wherever a position on the tape is intended to carry data.

Thus the Amicode inverse teletypewriter coded tapes and tape readers can be used wherever extremely rapid automatic reading and transfer of data is important, as for example, in serving the input devices of electronic data processing systems.

(F) *General*

The foregoing examples are sufficient to indicate the great usefulness of the Codamatic System and its various component modules. The examples given are not to be construed as the only, or limiting, applications. The flexibility of the Codamatic System is such as to make it valuable in an unlimited number of records keeping and accounting operations. Wherever it is desired to capture fixed and/or variable data automatically in machine language in a records keeping or accounting system, one or more elements of, or an entire, Codamatic System may be used.

III. SUMMARY

(1) Novel features of the Codamatic System include the storage of data in teletypewriter and other codes, counting, recording and reading, automatically, in machine language (teletypewriter and other codes), automatic reference to variable or fixed data stores automatically in accordance with a wired-in machine program, a new code, Amicode, which is unique, a completely new punch card (the Amicode Cards) and punch Card Reader, use of a common telephone dial to capture variable data, unusual circuits to automatically translate all captured data into machine language, a clock which operates in teletypewriter code, and a dial circuit which enables the human operator to erase his mistakes electrically.

(2) The coined words Codamatic, Cardamatic, Dialamatic, and Amicode are original with this inventor.

(3) The automatic machine inverse code, Amicode, is

original, novel and different from all other codes. Its use to encode punch cards makes possible the design of the Amicode Card Reader which has a minimum of moving parts and is the simplest card reader ever devised. Further, the Amicode cards cannot be torn by the Amicode Card Reader since they are not moved during the card reading action.

(4) The Amicode card reader is novel, original, different from all other card readers and useful. It stores and reads decimal digits and alphabetical characters in teletypewriter or other code. How it stores and reads teletypewriter code is demonstrated in this design description, but the same design principles may be used for the storage and reading of decimal digits and alphabetical characters in other codes.

(5) The Amicode Card Reader reads all data from Amicode cards and translates the data from the inverse teletypewriter code used on the Amicode cards to teletypewriter code, for collation with other fixed and variable data in teletypewriter code.

(6) The circuitry for continuously counting, recording, and reading variable information in teletypewriter code as demonstrated in the design of the Master Timer and the Alternate Master Timer is novel, original and useful. The design principle can be used to devise counters, recorders, stores and read-out devices which operate in any other code.

(7) The Controller is original, novel and useful. It is so designed that the Amicode card readers and Dialamatic Stations may be used in any number and interchangeability, thereby giving the Codamatic System its great flexibility and expansability.

(8) The Cardamatic Time Clock is novel, original, useful, and different from all other time clocks, in that its output may be in visual forms or in machine language directly. Teletypewriter code is used as the machine language in the designs used in this description, but any other code may be used.

(9) The Dialamatic Time Clock is novel, original, useful, and different from all other time clocks. First, it has a dial input, second, it has a machine language output directly, and an optional visual record output (typed or printed listing or simply a visual time display system).

(10) By virtue of the unique design principles employed in the Master Timer, the Alternate Master Timer, the Controller, and the control and release circuits, it is possible to use any number of Cardamatic and Dialamatic Time Clocks interchangeably.

(11) Because teletypewriter code is used, the machine language outputs of the Codamatic System can be transmitted without change thousands of miles over standard commercially available communications lines to the remotely located Punch, converter, Flexowriter or teletypewriter to produce printed or typed copies or input media to a computer, automatically. Other codes may be used, as has been pointed out previously in this description. Teletypewriter code, however, is chosen to illustrate the principles because it can be used directly in commercially available communications systems.

(12) The Codamatic System has innumerable practical applications as pointed out in section II of this description.

(13) The Codamatic System, being of modular construction, may be made as small or as large as the needs of the user dictate.

(14) The Cardamatic and Dialamatic Stations may be used anywhere for the capture, storage, translation into machine language, reading and recording in machine language, and recording in human language, any combinations and amounts of fixed and variable data.

(15) The individual components used are rugged, reliable and economical.

(16) The Amicode inverse teletypewriter code tape can be read faster with an Amicode tape reader than any

other punched tape available. It is new, novel and useful because of its high speed operation.

(17) The Amicode fast tape reader is electrically and physically the same as the Amicode Card Reader with this difference: a tape driving mechanism is added to the Amicode Card Reader to move the Amicode tape past the pole contactors of the Amicode Card Reader. Such driving mechanisms may be purchased commercially.

(18) The Amicode Tape need not use the inverse teletypewriter code exclusively. Any other inverse code may be used, and the Amicode Tape Reader (Amicode Card Reader with tape motor attachment) may be wired to read any other inverse code.

(19) The inverse teletypewriter code may be transmitted and received over ordinary teletypewriter communications lines with an Amicode transmitter and receiver, or a standard teletypewriter transmitter and receiving perforator.

(20) While relays, switches, and stepping switches are used throughout because of their ruggedness and economy, the Codamatic System is not limited to their use. All the circuits may be designed and all the devices may be designed by use of standard electronics engineering techniques and practices so that vacuum tubes, transistors, and other solid state devices, and electronics circuits can be used instead of the electro-mechanical devices and electrical circuits shown.

While I have illustrated and described several specific embodiments of my invention, it will be understood that these are by way of illustration only, and that various changes and modifications may be made within the contemplation of my invention and within the scope of the following claims.

I claim:

1. A business machine comprising means for storing permanent source data in teletypewriter code, coded input means including a punch card for introducing, into said machine, additional data in teletypewriter code, a time clock providing input signals, means for converting and introducing said signals into said machine in teletypewriter code, means for automatically combining and translating all of said input data into one message in teletypewriter code, and output means for reproducing said combined data.

2. A business machine comprising means, including punched cards, storing fixed data in teletypewriter code, means for introducing, into said machine, variable time data, including output signals from a time clock and means responsive to said output signals for telling time in teletypewriter code, and means combining and translating said fixed and variable data in the form of a single message.

3. A business machine comprising input means for introducing data into said machine, said input means comprising a card having, at least, a surface of electrically conducting material, said card having a plurality of

punched holes arranged in inverse teletypewriter code, movable means, including a plurality of wiping contacts extending substantially at right angles to said card for scanning said card while the card is stationary by contacting the unpunched portions of said card, and means responsive to said movable means for initiating and for transmitting a plurality of electrical impulses corresponding to teletypewriter coded language.

4. A business machine as recited in claim 3 together with input means for introducing fixed source data in teletypewriter code language, said movable scanning means including means for translating encoded data which is the sum of said input data.

5. A business machine as recited in claim 3 together with a variable data input means including a time clock and comprising a plurality of movable electrical contacts relatively positioned in space and arranged to denote time in teletypewriter code language, said movable scanning means being wiped over said plurality of electrical contacts to read time in teletype code language.

6. A business machine comprising means for electrically storing permanent data, punch translating means responsive thereto, card-operated input means for introducing additional data into said translating means, a plurality

25 of card reading stations for said last mentioned data, a plurality of telephone dial-operated input stations for introducing variable and permanent data into said translating means, a master timer for introducing, into said translating means, time data by periodically generating

30 electrical impulses, a controller for selecting one of said card reading stations and said telephone dial-operated stations and for controlling the sequence of electrical operations, means for rendering inactive all but the selected stations, said translating means combining and translating all of said data as a single teletypewriter coded message.
